UNITED STATES PATENT OFFICE.

FERNAND ROCROY, OF ROANNE, FRANCE.

COMPRESSED-GAS SHOOTING ARM.

Application filed January 11, 1926, Serial No. 80,623, and in France March 26, 1925.

The object of my present invention is to provide certain new and useful improvements in shooting arms of the type wherein the expansion of gas compressed in a reservoir is used for the propelling of the projectile. My improvements consist more particularly of an automatic opening and closing device for the reservoir, whereby a sudden discharge of compressed gas will be produced by its own pressure and an improved loading device, whereby the projectile may be inserted into the barrel of the arm at the point where gas is discharged from the reservoir.

My improved devices are applicable to various shooting arms such as rifles, guns, pistols, ordnance mechanical guns and the like.

By way of example I have illustrated in the accompanying drawings an improved rifle of my invention operating with compressed air produced by a compressing pump provided on the arm and actuated manually, the rifle being placed horizontally in shooting position.

Fig. 1 is an elevation of the arm.

Fig. 2 is a plan view thereof.

Fig. 3 is a longitudinal section of the arm on a vertical plane passing through the axis of the barrel.

Fig. 4 is an enlarged sectional view of the parts of the arm shown in Fig. 3, to wit: the compressed air reservoir with its internal opening and closing device, the loading device for the insertion of the projectile into the barrel and a fragment of the compressing pump. In this view the loader closes the projectile inlet.

Fig. 5 is an enlarged view of the longitudinal section shown in Fig. 3 of the barrel of the arm. In this view the loader uncovers the projectile inlet and the projectile may be inserted into the barrel.

Fig. 6 is a fragmental cross sectional view of the compressed air reservoir on a vertical plane A—A Fig. 4.

The arm comprises a butt-end 1 and a recessed stock 2, the air compressing pump arranged in the recess of the stock with its piston 3 and piston-rod 4. The compressed air reservoir 5 is a cylindrical tube placed tangentially to the compressing pump and connected thereto, through channels 6 and 7, the channel 6 being normally closed by a valve 8. The reservoir 5 is closed at one end near the cock 9 by means of a valve 10 hav-

ing a movable head 11 opened by the shock of the cock to open the communication between the portion 12 of the reservoir and the outer atmosphere through channels 13 and 14 and ports 15.

Slidably arranged in longitudinal direction within the reservoir is a part 16 termed "shutting-piston", one end of which carries a piston 17 and the other a swelling or bead 18. The piston 17 divides the reservoir into two compartments 12 and 19. Said piston has an inner channel 20 extended by another of larger diameter 21 discharging into the compartment 19 of the reservoir through ports 22. The channel 21 contains a spring 23 acting on a ball 24 for automatically opening and closing the channel 20 and enabling air to enter the compartment 19 at the same time preventing air from being discharged therefrom at this end.

A spring 25 of suitable strength resting on a stationary annular base 26 has tendency to urge the shutting piston towards the barrel. The swelling or bead 18 of the shutting piston has on its outer periphery a spider the arms 27 of which rest on the inner wall of the reservoir and serve to guide the shutting piston and hold the same well centered in the reservoir. The body of the swelling is cylindrical and recessed in the shape of a cup with an annular bottom packing of india-rubber 28 held in place by means of a screw 29 (Figs. 4 and 5). Said packing forms a seat for the end of the movable part 30 constituting the loader, and it will close the reservoir by the action of the spring 25.

The barrel 31 is formed of an internally cylindrical tube, secured by its part 32 to the tube 5 of the reservoir so that the axes of both will be alined and the end of the part 32 of the barrel rest on the annular packing 33 of the loader 30.

The loader is made generally in the shape of a hollow cylinder the inner diameter of which is equal to that of the barrel. The rear part thereof has a cylindrical swelling 34 which receives the annular packing 33. Said rear part of the loader rests on the packing 28 of the shutting piston of the reservoir and is adapted to longitudinally slide upon pulling a knob or button 35 rearwardly in a cylindrical recess 36 at the base of the barrel, whilst the swelling 34 will slide within the reservoir 5 so as to uncover the inlet 37 for the projectile 38 and enable

the latter to be inserted into the recess 36 of the barrel. In this operation the rear part of the loader which rests on the packing 28 of the shutting piston of the reservoir, causes said shutting piston to move rearwardly against the action of the spring 25, the shutting piston and loader then assuming the positions shown in Fig. 5. Upon the release of the pulling knob 35 said parts will be brought back by the expansion of the spring 25 to their initial positions shown in Fig. 4 and the projectile will enter the interior of the loader. Said device will secure the tightness of the reservoir.

15 The operation of the arm may thus be explained as follows:

The cock 9 will be raised, the reservoir being then tightly closed. The knob 35 of the loader will be moved rearwardly so as to uncover the inlet 37 for the projectile and the latter will be inserted. The reservoir will be set under pressure by means of the air pump, air entering the compartment 12, then the compartment 19 raising the ball 24 which will be forced back upon its seat by the spring 21 after each admission of air.

If the compression pump is not operated, the compartments 12 and 19 of the reservoir 30 will not be in communication, but the pressure of air is equal in both compartments. If this pressure is deemed to be sufficient for shooting, the arm will be ready for shooting.

If it is desired to shoot, the trigger 39 will 35 be actuated as in ordinary arms, whereupon the cock 9 will strike the movable head 11, whereby the valve 10 will be opened to allow the escape of air contained in the compartment 12 of the reservoir into the outer atmosphere through channels 13 and 14 and ports 15. Owing to the vacuum thus produced in the compartment 12 and the pressure in the compartment 19, the shutting piston will be suddenly forced backwardly. 40 Then the opening of the loader 30 will be uncovered and compressed air from the compartment 19 will suddenly enter said loader and afterwards the barrel to force the projectile forwardly for shooting.

45 When the spring 25 will force the shutting-piston 16 forwardly to its initial position, the swelling 18 thereof closing the opening of the loader. Upon raising the cock, the reservoir will be ready for charging.

50 It will be obvious that the hand compress-

ing pump may be replaced by a tube containing one or more charges of compressed gas. Likewise for long range arms such as mechanical guns, ordnance and the like. I 60 may use any gas supplying device such as a compressor, highly compressed gas containing flasks and the like, such devices being connected to the reservoir of the arm by any suitable conduit provided if necessary 65 with a pressure reducing device and a pressure gauge, such devices being made integral with the arms or independent from the same..

Having now fully described my said invention, what I claim and desire to secure by Letters Patent, is:

1. In a compressed gas shooting arm, the combination with the barrel and a compressed gas reservoir, and an opening in 75 said reservoir discharging into the barrel, a shutting piston slidably arranged within said reservoir and dividing the same into two compartments, a valve closing one of said compartments towards the cock of the arm, 80 a cock adapted to strike said valve to connect said compartment to the outer atmosphere, suitable springs cooperating with said shutting piston and valve to move them automatically back to their initial positions, 85 substantially as set forth.

2. In a compressed gas shooting arm, the combination with the barrel and a compressed gas reservoir, and an opening in 90 said reservoir discharging into the barrel, a shutting piston slidably arranged within said reservoir and dividing the same into two compartments, a valve closing one of 95 said compartments towards the cock of the arm, a cock adapted to strike said valve to connect said compartment to the outer atmosphere, suitable springs cooperating with said shutting piston and valve to move them automatically back to their initial positions, a loader adapted to slide longitudinally 100 within a portion of the barrel at the discharge end of said reservoir, a knob arranged outside the arm for operating said loader and inserting a projectile into the barrel at the discharge end of the reservoir, 105 and means for moving the loader automatically back to its initial position, substantially as set forth.

In testimony whereof I have hereunto set my hand.

FERNAND ROCROY. [L. S.]
